UNITED STATES PATENT OFFICE.

CHARLES W. CAMFIELD, OF NEWKIRK, OKLAHOMA.

DESIGN FOR A WATCH CHARM.

Application filed June 19, 1922. Serial No. 2,729. Term of patent 7 years.

To all whom it may concern:

Be it known that I, CHARLES W. CAMFIELD, a citizen of the United States, residing at Newkirk, in the county of Kay and State of Oklahoma, have invented a new, original, and ornamental Design for a Watch Charm, of which the following is a specification, reference being had to the ac-

companying drawing, forming part thereof.

The figure is a perspective view of a watch charm embodying my design.

I claim:

The ornamental design for a watch charm as shown.

C. W. CAMFIELD.
